ARTICHOKE DISH

Mary E. Gorzelnik, Bakersfield, Calif.

Application July 7, 1958, Serial No. 51,657

Term of patent 14 years

(Cl. D44—15)

FIG. 1

Fig. 1 is a perspective view of the artichoke dish.
Fig. 2 is a view of the artichoke dish in front elevation.
Fig. 3 is a plan view of the artichoke dish shown in Fig. 1.

Fig. 4 is a transverse sectional view through the artichoke dish taken on line 4-4 of Fig. 3.

I claim:

The ornamental design for an artichoke dish, as shown.
